GAME APPARATUS

Philip Faber, Brooklyn, N. Y., assignor to Stanley
Faber, Brooklyn, N. Y.

Refiled for abandoned application Serial No.
222,434, August 21, 1938. This application July
27, 1939, Serial No. 286,770

3 Claims. (Cl. 273—123)

This invention relates to amusement apparatus, and, more particularly, aims to provide an improved game of the kind incorporating a target, and a missile to be directed and propelled toward 5 the target by a person playing the game.

As herein employed, the term target is used to include any field of play toward which the missile is directed and propelled by a person playing the game and which includes a plurality 10 of chutes, openings, cups, or any equivalent through or into any one of which the missile may pass or come to rest for scoring or preparing for the scoring of a game point. All devices such as those last named will herein generally be called 15 receptors. As the term missile is used herein, it includes a puck, ball or other slideable or rollable or projectile object of play, whatever be its nature, so long as it is either thrown through the air or travelled over a guiding surface or surfaces 20 to or toward a target including a plurality of receptors.

In a now favored way of carrying out the invention, the missile is traveled over a guiding surface all the way to the target, and it is desirably a ball to be rolled along said surface; and the receptors are apertures. When the invention is thus carried out, it provides what is commonly known as a rolling ball game.

A popular type of amusement apparatus of the 30 general class to which the present invention pertains, is one wherein at the far end of the apparatus and in back of the target there is an upstanding structure having a translucent panel illuminable, usually by electric bulbs behind the 35 same, to give a signal that the game has been won; with this signal including a plurality of signalling elements each of all or of a certain group of which must be illuminated, but each as the result of a separate scoring play of the 40 missile relative to the target, in order to give the win signal.

The present invention has been made with the 45 idea of providing a novel and valuable type of apparatus of the general class last-named, and one preferably having the features just recited, but one in which the object is attained of providing a number of different possible ways of winning the game which is many times greater even than such a large possible number of different ways of winning the game as is taught by U. S. Patent No. 2,127,396 to me.

This application is filed in place of and as a substitute for application for the same subject matter, Serial No. 222,434 filed August 21, 1938, 55 which latter application became abandoned.

In order to attain this object, the present invention provides, in combination with a plurality of signalling elements considerably less in number than the number of target receptors, means setting up an operative relationship between 5 various target receptors and various signalling elements in such manner that when the missile coacts with any one of a particular plurality of said receptors a particular one of said signalling elements is actuated. As the invention is preferably carried out, the arrangement is such, also, that when the missile coacts with any one of a different particular plurality of the target receptors, a different particular one of the signalling elements is actuated, and when the missile coacts with any one of still a different particular plurality of the target receptors, still a different particular one of the signalling elements is actuated; and so on.

Other features and advantages of the invention 20 will be apparent hereinafter.

In the accompanying drawings, in which I have shown a now preferred form of the invention as illustrative of the many possible ways in which the invention can be carried out:

Fig. 1 is a perspective view of said embodiment, in the present case shown as a coin-actuated one.

Fig. 2 is a central longitudinal vertical section taken through the game of Fig. 1, on a somewhat enlarged scale.

Fig. 3 is a horizontal section, taken on line 3—3 of Fig. 2.

Fig. 4 is mainly an electrical diagram showing a simplified circuit and adjuncts thereto, certain of which latter are shown also in Figs. 1 and 2.

Fig. 5 is a side elevation of one of five electromagnetic devices seen in rear elevation in Fig. 4.

Fig. 6 is an end elevation of one of said devices.

Referring generally to the exemplifying embodiment of the invention shown in the drawings, the same is one in which, for the purposes of illustration merely, and not by way of limitation, but merely to show in detail a present preference based on great public interest found by actual test, the winning signal comprises a 45

plurality of signalling elements all of which must be actuated, but not in any special order—these signalling elements in the present case being five in number, and being transparencies showing the component letters of the word 50 "Bingo"; the target receptors are present in such number that the total of these is an even multiple of the total of signalling elements making up the winning signal; this multiple is obtained by taking up the square of the number of said com- 55

ponent letters, that is, there are twenty-five target receptors; and each target receptor of a different one of five different ones of five groups of these receptors, each group comprising five receptors, is assigned to a different one of the signalling elements.

As shown best in Fig. 1, where the target is indicated at T, the same is seen to comprise twenty-five apertures 18 in a table 19 along which a ball M is rolled from the end of the table opposite to the target-carrying end thereof, at which first-mentioned end of the table the player stations himself. As will also be noted from Fig. 1, five of said apertures are marked "B," five others are marked "I," five others are marked "N," five others are marked "G," and five others are marked "O." Further, as here shown, similarly marked apertures are nowhere in line with each other along the general line of travel of the ball, that is, in a direction substantially parallel with the longitudinal center-line of the table 19.

Referring now to Figs. 1, 2 and 3, the table 19 forms the top wall of a main horizontal casing 20, the latter also including a floor 21 spaced below the table, so as to provide a chamber 22 between the floor and the table. The chamber 22 is closed in by suitable end walls 23 and 24, and by side walls 25 and 26. Each of these latter walls is upwardly extended as indicated at 25a and 26a along the major part of the table length, and the end wall 24 is similarly extended across the width of the table; so that these upward wall extensions provide between them an alley along which the missiles may be directed and propelled by the player while he is at his station, to prevent the missile, desirably a rubber ball, from inadvertently being sent over a side edge of the table or over an edge of the table beyond the target.

At the target carrying end of the table 19, the structure 20 is extended as an upright casing 27, spanning the width of the table; this casing for carrying the B, I, N, G and O translucencies 21 aforesaid, and other translucencies 28 for indicating, when desired, the number of balls played, that is, rolled toward the target and passed through any one of the target apertures 18, all as below explained.

The structure 20 may, of course, be mounted in any suitable place or manner; but, in the present case, the same is shown as supported on four table-legs 29.

It will be noted that the table 19, and also the floor 21, are downwardly inclined toward the player's end of the table. When the ball M passes down through any of the target apertures 18 it enters the chamber 22 and is received on the floor 21, to roll down along the same until coming to rest in a pocket 30. Above this pocket 60 is a hand-hole opening 31, so that the ball can be retrieved by the player, to be again rolled over the table toward the target T, each time the ball is returned to the pocket.

Adjacent to each target aperture 18 is a normally open switch 32 suitably secured to the underside of the table 19; these switches adapted to be momentarily closed incidental to the missile dropping through the aperture associated with a particular switch.

Said switches 32 are for closing circuit subdivisions of electrical means according to an arrangement such that when the missile passes through any of the five B apertures 18, the B translucency 21 will become illuminated; when 75 the missile passes through any of the five I aper-

tures 18, the I translucency 21 will become illuminated; when the missile passes through any of the five N apertures 18, the N translucency 21 will become illuminated; and so on. This wiring of the switches 32 is indicated clearly in Fig. 3, 5 where a common supply wire marked 33 in Figs. 3 and 4 (and additionally marked CS is Fig. 3) is provided for serving in parallel all the switches 32—but which wire, to simplify Fig. 3, is actually shown as connected only to the five switches 32 10 serving the row of apertures 18 running lengthwise of the table 19 at the extreme right of Fig. 1. A similar showing is made in Fig. 3 of the wires which go to the terminals of all the switches 32 other than the terminals thereof connected to 15 the common supply wire 33. Of these five wires last referred to, that marked 34 in Figs. 3 and 4 (and additionally marked B in Fig. 3), is shown as going in parallel to all the five B apertures 18 of the target. In the same way, although not so 20 shown in Fig. 3, the wire marked 35 in Figs. 3 and 4 (and additionally marked I in Fig. 3) goes in parallel to all the five I apertures 18 of the target; the wire marked 36 in Figs. 3 and 4 (and additionally marked N in Fig. 3) goes in parallel 25 to all the five N apertures 18 of the target; the wire marked 37 in Figs. 3 and 4 (and additionally marked G in Fig. 3) goes in parallel to all the five G apertures 18 of the target; and the wire marked 38 in Figs. 3 and 4 (and additionally marked O in Fig. 3) goes in parallel to all the five O apertures 18 of the target.

By the laws of choice and chance of elementary algebra, there are 3,125 possible ways of winning the game by causing all the five translucencies 21 making up the word Bingo to become lighted as the result of having the ball M pass through only five of the apertures 18 of the target T. That is to say, referring to the translucencies 21, the I can be illuminated in any one 40 of five different ways, following the illumination of the B in any one of five different ways, reaching a total of 25 permutations; and at the same time, the illumination of the N is possible in any one of five different ways, reaching a total of 125 permutations; while the illumination of the G is possible in any one of five different ways, raising the total of permutations now to 625, and the illumination of the O is possible in five different ways, giving, finally, a total of 3,125 50 permutations, or different possible ways of winning the game.

As is well-known in the art, the game can be played individually, and released for such play by insertion of the proper coin in any suitable type 55 of coin-operated device, such as that indicated at 39; the same here shown as including, conventionally, a coin receptor 40, a coin-slide 41, and a cross-bar which on inthrust of the coin-slide strikes and actuates a setter 43a for a familiar type of timer 43. Such a timer is ordinarily operated by a spring wound up by such setter as a result of an inthrust of the coin-slide, and can usually be set to operate for any desired time 60 interval, during which period of operation a normally open main switch for the electrical circuit including the switches 32 or equivalents is maintained closed.

In such operation of the game, it is advisable, also, as taught, for example, in the aforesaid 70 patent to me, to count the number of times the missile is propelled toward the target and it passes through one of the apertures 18, so that the incentive to the player will not only be to cause the winning signal to be flashed before the 75

time-interval available has expired, but also to accomplish this with the least possible number of such uses of the missile. To indicate this, in Fig. 1 the upright casing 27 is shown as having its front panel 44 such as to carry, above the legend Electric bingo thereon, the horizontal row of translucencies 28 aforesaid; these latter here being ten in number and carrying respectively the numbers from 1 to 10, and in the present case 10 being individually lighted by separate electrical bulbs one of which is shown at 45 in Fig. 2. Any suitable electrical arrangement can be provided to illuminate these translucencies in the order of their ordinal numbering, for instance as 15 taught in the aforesaid patent to me; as by successive closings of a normally open switch shown at 46 in Figs. 2 and 3, each time the ball M passes thereover, to which end the chamber 22 is shown as provided with partitions 47 to guide 20 the ball always to pass over said switch while on its way down along the chamber 22 below the target T back to the pocket 30.

According to the present structure, it will be noted, the switch 46 is closed by the ball following each propulsion thereof to the target, regardless of whether the ball passes through an aperture 18 or not; because of the presence of the chevron-barrier 48 so placed across the table 19, in relation to a pair of like openings 49 at 30 opposite sides of the table, that whenever the ball is propelled to the target, as incidental to a ball leap over said barrier, it must, if it fails to pass through an aperture 18, enter one of said openings 49, and so be guided by the partitions 35 47 to roll over the switch 46.

Referring now particularly to Fig. 4, the normally open switch of the timer 39 is shown at 50.

This switch is connected at one terminal to a wire 51 leading from one end of the secondary 40 coil of a transformer 52, and is connected at its other terminal to a wire 53 leading to another, and a normally closed, switch 54.

The illustration of the switch 54 is, like that of the other showings of Fig. 4, essentially dia- 45 grammatic, to simplify the description. Further to shorten the description and make easy an understanding of the operation of the electrical features of the apparatus as here shown, the circuit connections are so delineated that compara- 50 tively heavy lines are used for the wires which will be assumed to be the "return" conductors relative to the secondary of the transformer 52 as to all circuits and circuit-subdivisions, and, in addition, small arrows are placed alongside many 55 of these return conductors so that they can readily be traced back to the end of the secondary of the transformer 52 opposite to the end thereof to which the wire 51 is connected.

The elementary wiring arrangement shown in- 60 cludes primarily what may be termed two main circuits; these being what may be called the operating circuit normally open at the switches 32 but normally closed at the switch 54, by way of the contacts 55 and 56 thereof, and what may be called the clearing circuit normally open at the switch 54 but closable by way of the contacts 57 and 58 thereof. As will become clearer later, the operating circuit includes or has associated therewith a win-signal circuit, closed for 65 the first time when the operating circuit has been properly modified by a playing of the game such that the missile M has been passed through five of the apertures 18 of the target T with each of said apertures allocated to a different 70 one of the component letters of the word Bingo. 75

The switch 54, shown as having a pivoted switch-arm 59 carrying thereon the contacts 56 and 57, is normally maintained in the position illustrated by a retractile spring 60.

Referring first to the win circuit, this is for the purpose of giving one or more signals, additional to the flashing on of all the five letter-parts of the translucencies 21 of Fig. 1 by five light bulbs 61 (see also Fig. 2, where one such bulb 61 is shown), when as aforesaid any five of the switches 32 associated with five of the target apertures 18 each marked with a different one of the letters B, I, N, G and O, have all been closed in any sequence. In the present case, such additional win signal is shown as comprising an electric light bulb in a glass hood 62, this last as shown in Figs. 1 and 2 conveniently placed on top of the upright casing 27, and the bulb therein being interposed in the win circuit. Such a visual signal, and also an audible signal, as an electric bell (not shown), to be simultaneously actuated when the win signal is closed, is particularly useful where the present game is employed as one of a bank or battery of a plurality of games, and where the 25 players, each using one of the games, are in a contest with each other, and which contest is won by the player who first succeeds in closing the win circuit.

The win circuit, beyond the wire 51 and the timer switch 50, includes the wire 53, the switch-arm 59 and its contact 56, the contact 55, a wire 63, a wire 64, and beyond the last of five relays 65, 66, 67, 68 and 69, a wire 70, a wire 71, and a wire 72 back to the secondary of the trans- 20 former.

This win circuit is normally open, therefore, at five gaps therein, these gaps being, respectively, between the wire 64 and a wire 73 joining the relays 65 and 66, between said wire 73 and a wire 74 joining the relays 66 and 67, between said wire 74 and a wire 75 joining the relays 67 and 68, between said wire 75 and a wire 76 joining the relays 68 and 69, and between said wire 76 and a wire 70. 45

In Fig. 4, as will be noted, different ones of these relays are also marked with different ones of the component letters of the word Bingo; different ones of the switches 32, of the five thereof marked 32 in this view (these five 50 switches corresponding to the switches 32 serving the five apertures 18 which in the target T of Fig. 1 make up a horizontal row of these apertures immediately in front of the upright casing 27), are also marked with a different one of the 55 component letters of the word Bingo; and different ones of the bulbs 61 serving different ones of the component letters of the word Bingo which constitute the translucency 21 of Fig. 1, are indicated in Fig. 4 by the dot-and-dash out- 60 lining of said component letters.

Note further from Fig. 4 that in agreement with the showing of Fig. 3, a wire 34 goes to one terminal of that one of the last-mentioned switches 32 also marked B, a wire 35 goes to one 65 terminal of that one of said switches 32 also marked I, a wire 36 goes to one terminal of that one of said switches 32 also marked N, a wire 37 goes to one terminal of that one of said switches 32 also marked G, and a wire 38 goes 70 to one terminal of that one of said switches also marked O.

Also note from Fig. 4 that from the wire 34 extends a wire 34' having four branches in parallel between the braces marked B'; from the 75

wire 35 extends a wire 35' having four branches in parallel between the braces marked I'; from the wire 36 extends a wire 36' having four branches in parallel between the braces marked 5 N'; from the wire 37 extends a wire 37' having four branches in parallel between the braces marked G'; and from the wire 38 extends a wire 38' having four branches in parallel between the braces marked O'. As will be understood, each 10 of these parallel branches from the wire 34, goes to a separate one of the four switches 32 (other than the switches marked 32 and also B in Fig. 4) serving the apertures 18 of the target marked B in Fig. 1; each of said branches from the wire 15 35' goes to a separate one of four switches 32 serving the I apertures 18; each of said branches from the wire 36' goes to a separate one of four switches 32 serving the N apertures 18; and so on, similarly, as to the wires 37' and 38', their 20 branches for, respectively four G target apertures 18, and four O target apertures 18—while from the common supply wire 33 for the five switches 32 marked also B, I, N, G and O, respectively, in Fig. 4, a branch 33' extends, having twenty branches thereof in parallel each for serving one of the remaining twenty of the twenty-five switches 32 as indicated by the approaches of these branches to the braces associated with the indications B', I', N', G' 25 and O'.

In brief, the arrangement is such, as will be seen from a mere inspection of Fig. 4 (but as will be explained in detail below), that when any switch 32 associated with a B aperture 18 of Fig. 1 30 is closed by passage of the ball B through that aperture, the relay 69 will be operated; when any of said switches associated with an I aperture 18 of Fig. 1, the relay 68 will be operated; when any of said switches associated with an N 35 aperture 18 of Fig. 1, the relay 67 will be operated; when any of said switches associated with a G aperture 18 of Fig. 1, the relay 66 will be operated; and when any of said switches associated with an O aperture 18 of Fig. 1, the relay 40 45 65 will be operated.

The purpose of operating any such relay is to close two circuit subdivisions of the operating circuit, one for flashing on the appropriate bulb 61, and the other for closing one of the aforesaid 50 gaps between the wire 64 and the return wire 70, to wit, the gaps intervening between said wire 64 and the wires 73, 74, 75 and 76 (these last four wires joining adjoining relays) and the return wire from the last relay in the series—thereby 55 to transform the last-referred to circuit subdivision of the operating circuit into an effective win circuit because a closed such circuit.

And in this connection it is pointed out that each relay includes, in addition to an actuating 60 electromagnet and an armature attracted thereto, two pairs of normally spaced contacts, each pair in a separate circuit subdivision, but rearranged by energization of the magnet to close both said circuit subdivisions.

65 Referring at this point to Figs. 5 and 6, the relay 65 there shown will be now described. As all the relays are alike in construction and operation, the description of this one will suffice for all.

70 The electromagnet thereof is indicated at 77, and its armature at 78, this armature being pivotally hung at 79 and carrying an L-shaped bracket 80. Through suitable slots (not shown) in the bottom or horizontal limb of this bracket 75 extend the lower ends of a pair of sidewise spaced

depending leaf-spring carriers 81 each having a contact normally spaced from a cooperant contact, with each of the latter contacts on one of a pair of sidewise spaced depending leaf-spring carriers 82. One of these sets of contacts is for flashing on the proper bulb 61, and the other set is for closing one of the aforesaid five gaps in the win circuit and that one of these gaps at one side of the relay. In the case of the relay 65, the gap to be closed is that between the wires 64 and 73 of Fig. 4.

The upper ends of the four leaf-spring carriers 81 and 82 are suitably anchored between blocks 83 of insulation secured to a mounting 84 which carries part of the pivotal support 79 and to which the magnet 77 is attached.

When the relay is energized as above, the armature 78 and the bracket 80 are swung to the positions shown in broken lines in Fig. 5, both of the two sets of contacts, each set on one pair of carriers 81 and 82 and the other set on the other pair of these carriers, are brought together, to circuit closing position; and the parts are thus locked by latching engagement between the bracket 80 and a toothed dog 84 pivoted at 85 and biased in the direction of the arrow 86 by a spring 87.

The relay 65 is so interiorly wired or otherwise suitably provided with interval conductors, that, referring to Fig. 6, a binding post 88 is electrically connected to the carrier 81 at the left in Fig. 6, and a binding post 89 is electrically connected to the carrier 81 at the right in Fig. 6.

Referring to the contact-carriers 81 and 82 at the left in Fig. 6, the wire 64 leads to the binding post 88 and therefore to the carrier 81, while from the binding post 89 extends a wire 73 for connecting the carrier 82 with a binding post of the next relay 66 to the right in Fig. 4 beyond the relay 65 as shown in Fig. 4, the last-mentioned binding post corresponding to the binding post 88 of the relay 65. In the same way the wire 74 couples up the relays 66 and 67, the wire 75 couples up the relays 67 and 68, and the wire 76 couples up the relays 68 and 69.

Referring now to Fig. 4 and to the contact-carriers 81 and 82 at the right of each relay, a wire 90 leads from the binding post 89 of relay 65 to the appropriate bulb 61 of the translucency 21, and a wire 91 leads to the carrier 82 of relay 65—it being noted that this wire 91 is an extension of the aforesaid wire 38 which, in parallel with the wire 38' serving all the switches 32 associated with the appropriate target apertures 18, is itself an extension of the common supply wire 33. In the case of the relays 66, 67, 68 and 69, the wires corresponding to the wire 90 from the relay 65 are, respectively, wires 92, 93, 94 and 95; and the wires corresponding to the wire 91 to said relay 65 are, respectively, the wires 96, 97, 98 and 99.

From each of the wires 91, 96, 97, 98 and 99 is a branch for acting as a supply wire to the winding of the electromagnet of the associated relay; these branches being shown at 100, 101, 102, 103 and 104.

The return wires for these windings are marked 105, 106, 107, 108 and 109, all leading, through the return wires 71 and 72, back to the secondary of 70 the transformer.

The return wires for the bulbs 61 are marked 110, 111, 112, 113 and 114, all leading, through the return wire 72, back to the secondary of the transformer.

Operation

Whenever any switch 32 of any of the letter series matching any of the component letters of the word "BINGO" is closed by passage of the ball M through an appropriate target aperture 18, the magnet of the proper relay is momentarily energized, to close both the switch elements of that relay (these switch elements being the two pairs of contact-carriers 81-82); and these switch elements will be held closed by the latching means, including the toothed dog 84 of Figs. 5 and 6, if the relay 65 is the one operated or by a like latching means if it is another relay which is operated. Thereby, the appropriate bulb 61 will become and stay lighted; and one of the aforesaid five gaps in the win circuit will be closed. As soon as the ball is passed through five differently lettered apertures 18, regardless of the order of such letters, all five of these gaps will be closed (that is, all the wires 64, 73, 74, 75, 76, and the return wire beyond the relay 69, will be made in effect one conductor), and, as the translucency 21 shows for the first time the complete word Bingo, the win circuit will be closed, and the light within the hood 62 will be flashed on.

Such win circuit, from the secondary of the transformer 52, includes the wire 51, the switch-arm 59, the contacts 56 and 55, the wire 63, the filament of the light within the hood 62, the wire 64, parts of the five relays as above described, the intervening wires 73, 74, 75 and 76, and the return wires 70, 71 and 72 back to the secondary of the transformer.

In order to clear the game, it is merely necessary, in the arrangement illustrated, momentarily to move the switch-arm 59 against its spring 60. This can be done manually, or electrically, as by an electromagnet 115.

When the switch-arm 59 is thus moved, the win circuit is opened, so that the bulb in the hood 62 goes out; and, simultaneously, the clearing circuit is closed, this including five like magnet-releasors for the latching means associated with each relay. As shown in the case of the relay 65 (Figs. 4, 5 and 6), each such releasor includes an electromagnet 116 which, when energized, attracts an armature 117 carried by the adjacent dog 84, and so frees the bracket 80 to allow the latter to be restored to its full line position as shown in Fig. 5, by the resilient action of the leaf-spring contact-carriers 81.

The five magnets 116 thus associated with the five relays are simultaneously energized; and so all the lights 61 then on, are put out.

And, playing of the game can be started all over again, as soon as the switch-arm 59 is returned to the condition illustrated in Fig. 4, which can be done by manual release of said arm, or by breaking the circuit in which the magnet 115 is interposed.

Each of the magnets corresponding to the magnet 116 of Figs. 4, 5 and 6, is, as shown in Fig. 4, supplied with current by one of five parallel connections 118, 119, 120, 121 and 122 from a wire 122', leading from contact 58; these magnets having return connections 123, 124, 125, 126 and 127, leading, respectively, to the return connections 105, 106, 107, 108 and 109 serving the operating magnets for the relays; it being noted that the clearing circuit is made through the contacts 57 and 58 of the switch 54, as the win circuit is broken between the contacts 55 and 56 of said switch.

When the game is played individually, it is

desirable, particularly when coin-operated, to have an automatic timer, as shown.

When the game is employed as one of a battery of its fellows, where different players simultaneously compete with each endeavoring to be the first to obtain the win signal at his game, the timer can be eliminated—that is, the time for play can be that required for some one of the contestants to achieve the win signal.

When a knock-out means is employed, that is, a means to clear all other games in the battery of games last-mentioned except the winning game, when one of the games becomes the winning one, any suitable such means can be used, as, for instance, to energize in each of the non-winning games an electromagnet similar in function to the magnet 115. As here shown, however, in Fig. 4 the timer 39 is illustrated as having a switch 117 additional to the switch 50; this switch 117 being of the well-known type 20 which when actuated is snapped momentarily to closed position, as by a cam element (not shown) moved past the same by the actuator therefor, but immediately thereafter, as by a suitable spring (not shown), becoming restored to normal 25 open position. Such actuator could be the cross-bar 42 of Fig. 3. The purpose of this switch 117 is to cause momentary energization of the magnet 115, thereby to move the clearing circuit whenever (following the ending of a previous 30 playing of the game by the expiration of the appointed time interval measured by the timer 39), another playing of the game is about to be started, with the game used as an individual game. The circuit thus momentarily closed by 35 closing of the switch 117 includes the winding of magnet 115, a wire 119 leading from the switch 117, and a return wire 120 from said winding to the return wires 71 and 72 going back to the secondary of the transformer.

Aside from those mentioned other variations and modifications are possible within the scope of the invention, and parts of the improvements may be used without others.

I claim:

1. A game of the kind wherein there is a target including a bank of interceptors for a missile such as a rolled ball, wherein there is a signalling means including a plurality of individually operable electrically operating signalling devices each of which is normally in a different open circuit and all of which devices must be actuated to signal the winning of a game, and wherein each of said circuits includes a switch means operatively associated with a different interceptor and operable to close said circuit to actuate the appropriate one of said devices following interception of the missile by said interceptors—characterized by the combination of a plurality of said signalling devices to a total of N; a plurality of said interceptors to a total greater than N, such total large enough to provide more than one interceptor for each signalling device and with each interceptor for one signalling device only; and a plurality of said circuits to a total of N, each of said circuits having a plurality of circuit subdivisions, there being a different one of said circuit subdivisions for each interceptor, each of said circuit subdivisions being normally open, there being a different one of said switching means in each circuit subdivision which when closed closes that subdivision, and all circuit subdivisions in any circuit being in parallel in that circuit to cause closing of said circuit when any circuit subdivision thereof is 75

closed, whereby N different pluralities of interceptors are provided and any interceptor of any one of said pluralities is adapted on interception of the missile by that interceptor to actuate one of said signalling devices and a different one of said devices is actuated when the missile is intercepted by one of a different plurality of interceptors, provided the said interceptor is the first interceptor of its own plurality of interceptors to intercept the missile.

2. A game as in claim 1, in which the signal-

ling devices are arranged along a single line, and the interceptors are arranged in a plurality of lines each having N interceptors.

3. A game as in claim 1, in which the interceptors are clustered in such arrangement as to present rows extended in two substantially perpendicularly related directions across the target, in various of which rows the interceptors operatively associated with the same signalling devices are in different positions.

10

PHILIP FABER.
